DRILL GRINDING ATTACHMENT

Raymond G. Zenick, Burbank, Calif.

Application January 19, 1943, Serial No. 472,806

2 Claims. (Cl. 51—219)

1

My invention relates to a drill-grinding attachment for grinding machines.

One of the principal objects of this invention is to provide a grinding attachment for use in connection with the conventional grinder, and one which is particularly simple and economical of construction, easy to apply or install on the grinder, and one which is easy to operate.

Another important object of this invention is to provide an attachment of this class which is constructed so that it may be easily applied or attached and also effectively operated from or on either side of a revolving grinding wheel of the grinder.

An important object also of this invention is to provide an attachment of this class which may be readily adjusted to accommodate drills of various lengths.

A further important object of this invention is to provide an attachment of this class which may be readily adjusted toward or from the side faces of the revolving grinding wheel for decreasing or increasing, respectively, the clearance of the lips backwardly from the cutting edges of the drill.

Still another important object of this invention is to provide a very simple attachment of this class for easily and quickly adjusting the drill holder for varying the angles of the lips with respect to the axis of the drill, and to provide means in connection with the attachment for readily determining the desired angle.

With these and other objects in view as will appear hereinafter, I have devised a drill grinding attachment which will be hereinafter described in detail and particularly set forth in the appended claims, reference being had to the accompanying drawing and to the characters of reference thereon, which form a part of this application, in which:

Fig. 1 is a fragmentary front view of a conventional grinder showing my attachment mounted thereon, the attachment holding a conventional drill in position for grinding, dotted lines showing the attachment adjusted outwardly from the grinding wheel;

Fig. 2 is a fragmentary top view of the grinding wheel showing the drill to be ground in its initial grinding position, and showing by dotted lines the same drill when rotated counter-clockwise with the drill holding portion of the attachment for grinding the clearance backwardly from the cutting edge.

Fig. 3 is a sectional view thereof, taken through 3—3 of Fig. 1;

2

Fig. 4 is a fragmentary elevational view of the attachment, showing the pivotal portion from the side opposite to that shown in Fig. 1; and

Fig. 5 is a diagrammatic view of the side of the grinding wheel showing different positions of the lower lip during the process of grinding, said positions corresponding, respectively, to various positions of the attachment when adjusted progressively outwardly from the grinding wheel.

In the drawing, the grinder or grinding machine is designated 1, and is shown as supported on a suitable table 2. The grinder has an emery wheel, or other suitable grinding member 3.

My drill grinding attachment is supported on the table 2 and is shown positioned at the outer side, which is the right side of the grinding wheel.

As shown in the drawing, my attachment is supported on a pedestal 11 which has an elongated base consisting of two longitudinally slotted feet 11a. Through the slots of the feet extend anchor bolts 12. The anchor bolts have wing nuts 13 for adjustably securing the feet 11a on the table 2. The pedestal 11 has a vertical bore 11b into which extends a shank 14a of

25 the support 14 for swivelly supporting the support on the pedestal on a vertical axis. The drill holder 15 is provided at its underside and intermediate its ends with a downwardly extending lug 15a which is swivelly mounted on a horizontal

30 axis on a support 14, the latter swivel connection being provided by a bolt 17 which is also provided with an adjusting wing nut 18. The drill holding portion of the member 15 is normally inclined at a substantial angle to the horizontal.

35 This member 15 is provided at its upper portion with a longitudinal groove or channel 15b which is V-shaped, the angle of the V being substantially 90°.

The downwardly extending lug 15a has, at the 40 side opposite the upwardly extending lug 14b of the swivel or rotating support 14, a plate 16 on which is a dial. This dial has degree divisions or graduations adjacent the periphery. The graduations radiate from the axis of the bolt 17.

45 On the swivel or rotatable support 14 is an index mark 14c, which as shown in the drawing, may be seen through an arcuate slot in the dial member. There may also be provided an index mark 11c on the side of the pedestal, which may be used

50 when the drill holder lies in the plane of the feet.

The upper edge of the dial plate 16 is shown, in Figs. 3 and 4, as engaging the flat underside of a laterally extending lug 15c at the outer side and upper portion of the ear or lug 15a. The pivot bolt 17 secures the plate in position, and the

head 17^a of the pivot bolt is also shown as engaging this flat side of the lug 15^c. Thus, both the plate and the bolt are held against rotation.

Against the upper end of the drill holder, that is, the end normally adjacent the grinding wheel, is secured a drill guide 19, which is preferably made of tool steel, the same being shown best in Fig. 3. The drill D, to be sharpened and resting in the V-channel of the drill holder, is adapted to rest upon said guide, the portion of the drill resting on the guide being the opposite edge portions of one of the flutes of the drill.

From the other or lower end of the drill holder extends a long screw 20, this screw being positioned below the V-groove or channel but parallel with the vertex thereof. On the screw are screwably mounted a stop washer 21 and a lock wing nut 22. The drill to be ground and positioned in the V-channel is limited at its lower end by resting against the stop washer or member 21.

My drill grinding attachment is so constructed that the axis of the pedestal is adjusted a fixed position from the side face of the grinding wheel as indicated by A, this dimension being, for one form of my device, one and one-half inches. When so positioned, the end of the drill will extend approximately one-eighth of an inch beyond the upper end of the V-channel or beyond the tool steel guide or lip 19, with one of the cutting edges substantially vertical, as indicated by B 30 in Fig. 5. When the grinding wheel is rotated and the drill is swung about the vertical axis of the pedestal, a clearance of approximately 12° will be provided on the lip of the drill. If the dimension A is increased to A', the lip clearance 35 of the drill is slightly increased.

B, B', and B'' represent three positions of the lower lip of a drill in the process of grinding, and correspond respectively to three positions of the pedestal moved progressively outwardly or away 40 from the grinding wheel.

In the position of the drill holder, as shown by solid lines in Fig. 1, the lip will be ground at about 59° with respect to the axis of the drill. By reason of the pivotal mounting of the drill holder about a horizontal axis of the swivel or rotating

support 14, this angle may be increased or decreased as desired.

Though I have shown and described a particular construction, combination, and arrangement of parts and portions, I do not wish to be limited to the same, but desire to include in the scope of my invention the construction, combination and arrangement substantially as set forth in the appended claims.

10 I claim:

1. A drill grinding attachment for a grinding machine having a plane grinding surface, comprising a pedestal adapted to be mounted with respect to the grinding machine at a spaced distance from the grinding surface, a drill holder having a downwardly extending portion swivelly mounted on said pedestal, said drill holder having a drill positioning groove inclined upwardly toward the grinding surface, a stationary screw member secured to and extending from the lower end of the drill holder and positioned below and parallel to the groove therein, a drill stop screwably and rotatably mounted on the screw member, and a thumb nut on the screw member for 20 fixing the position of the stop on the screw member.

2. A drill grinding attachment for a grinding machine having a plane grinding surface, comprising a pedestal adapted to be mounted with respect to the grinding machine at a spaced distance from the grinding surface, a support swivelly mounted on said pedestal and extending thereabove, a drill holder having intermediate its ends a downwardly extending lug swivelly mounted on a horizontal axis on the upper portion of the support, said drill holder having a drill positioning groove for holding therein a drill adapted to extend at an angle toward the grinding surface, a dial plate on the lug, said plate having an edge engaging a flat portion on the lug, and a bolt swivelly supporting the drill holder on the support and securing the former in a pivotal position on the latter, the bolt also securing the plate to the lug, and the head of the bolt engaging said flat portion to hold the bolt against rotation.

RAYMOND G. ZENICK.
